IMPULSE REGULATOR ASSEMBLY

Arnold S. Soberg, Elmhurst, Ill., assignor to
Sochris Development Company, Chicago, Ill., a
corporation of Illinois

Application June 16, 1949, Serial No. 99,425

10 Claims. (Cl. 103—52)

1

This invention is directed to new and useful improvements in impulse regulator assembly of the type wherein pulsating pressure is provided to a pump assembly to move liquid from below ground to a storage tank or the like.

This device is particularly adaptable for use in a pump mechanism of the type in which a column of liquid leading from the top of a well to the source of supply is provided near the bottom with means whereby liquid from the source is entrapped each time a downward impulse is exerted on the column and, at the same time, a spring or a volume of air is compressed so as to add the thus entrapped liquid to the column when the downward impulse is released, whereby there is delivered to the surface an amount of liquid equivalent to the amount entrapped by the downward impulse. It is through a series of regular impulses that a steady flow of liquid is brought to the surface for delivery to a storage tank or elsewhere as desired. In such a device it is desirable to provide an efficient valve assembly cooperating with the pulsating means to direct pressure on the liquid column, to lead the pumped liquid to its reservoir, to prime the liquid column when necessary and to direct pressure so as to aid the pulsating means so that it may be actuated by less power.

The primary object of this invention is to provide an impulse regulator assembly of this type wherein passage to the liquid reservoir is adequately closed during exertion of pressure on the liquid column but open on release of the pressure.

Another object of this invention is to provide in such an assembly means for permitting the liquid column to be primed automatically and positively when needed.

A further object of this invention is to provide in such a device an arrangement of parts whereby less power is required to operate the pressure actuating means.

Other objects and advantages will be apparent from the following detailed specification.

In the drawings:

Fig. 1 is a schematic view of an impulse regulator assembly embodying this invention associated with a pump.

Fig. 2 is an enlarged sectional view of the impulse regulator assembly embodying this invention.

Referring to Fig. 1, reference character 1 designates a well casing within which is suspended an impulse actuated pump mechanism 2 of the type as described in detail in my copending ap-

2

plication Serial Number 680,295 filed June 27, 1946, now Patent Number 2,486,617, containing a reciprocating piston actuated by the variations of pressure on the liquid in the casing. 5 The cylinder 3 houses the pressure means and conduit 4 connects the cylinder 3 with the casing 1 through a load compensating reservoir or accumulator 5. The valve assembly is in housing 6 connected with cylinder or well casing 1 and a conduit 7 leads to liquid storage tank 8.

The details of the impulse regulator assembly are shown in Fig. 2. A piston 9 is reciprocally mounted in cylinder 3, rod 10 being of relatively substantial diameter and extending from the cylinder 3 to any desired operating mechanism.

Casing 6 is connected with the open end of cylinder 3 and is divided into main chamber 11 and outlet chamber 12. Chamber 11 is provided with a main port 13 connected with the top end of casing 1, a pressure inlet port 14 normally closed by valve 15 which is resiliently held in closed position by spring 16. A passageway 17 leads from the open end of cylinder 3 to port 14. Chamber 12 is provided with inlet port 18 opening to chamber 11, controlled by valve 19 and an outlet 20 connecting with conduit 7.

Valve 19 has a stem 21 to which is secured a piston 22 of larger diameter than valve 19. This piston 22 is reciprocally mounted in cylinder 23. 30 A passageway 24 leads from cylinder 23 to passageway 17 to direct liquid under pressure from cylinder 3 to the rear of piston 22.

A small priming port 25 opens chamber 12 to passageway 24 but is normally closed by valve 26 held resiliently in closed position by spring 27. A one way valve 28 is positioned in conduit 4 to admit liquid from the casing 1 but to prevent a reverse flow.

In operation, cylinder 3, casing 1, conduit 4, 40 reservoir 5, chamber 11 and conduit 24 are filled with liquid, e. g. water. Piston 9 is moved in cylinder 3, by any desired means, toward housing 6. The pressure thus created opens valve 15 against the spring 16 and the pressure is transmitted to the water in the pump casing 1 to depress the piston in the pump. The pressure is also transmitted to conduit 24 against piston 22 to keep valve 19 closed. This occurs because piston 22 is of greater area than valve 19.

The pressure against the water in the system is directed through valve 28 and conduit 4 to cylinder 3 back of piston 9 to relieve the load.

As piston 9 returns to its initial position the pressure is released, valve 15 closes and pressure within casing 1 reverses to direct water

55

therefrom to open valve 19 and thus water flows into chamber 12, out of outlet 20, through conduit 7 into storage tank 8.

If there is insufficient water in cylinder 3 and conduit 24, valve 26 will open on this return stroke and water will prime the cylinder.

The relatively large diameter of rod 10 decreases the volume of cylinder 3 behind piston 9 so the power required to return the piston to initial position is accordingly decreased.

Also in this reverse cycle of operation, piston 9 returns liquid under pressure through conduit 4. Valve 28 prevents this returned liquid from entering casing 1 and pressure is built up in reservoir 5. When pressure in conduit 4 and accumulator 5 equals the peak pressure in casing 1, this pressure will prevent valve 28 from opening. Several cycles, or forward and backward strokes of piston 9 may be necessary before the pressure in the accumulator equals that of the peak in the well casing. This pressure is utilized against the reduced area of the rear of piston 9 to relieve it of the load on the outward stroke.

Thus an impulse regulator assembly is provided in which less power is required to operate the pressure generating piston, the pressure created by the piston is used to seal the system during its generating stroke and means are provided for automatically priming the system.

The apparatus herein described may be operated successfully without the accumulator 5 and conduit 4. This is an optional addition but when omitted the power of the motor operating piston 9 must be increased. The effectiveness of the valve assembly remains whether or not accumulator 5 and conduit 4 is utilized.

I claim:

1. An impulse regulator assembly comprising a pressure power cylinder, a power piston, a casing to which the pressure is to be directed, a valve housing, a port in the housing to which the casing is connected, a port in the housing opening to the power cylinder, a port in the housing leading to a storage tank, a chamber in the housing opening to the casing, a pressure inlet port leading from the power cylinder port to said chamber, a valve normally closing said pressure inlet port, an outlet port from said chamber leading to said storage tank port, an outlet valve controlling said outlet port, a second piston of greater area than said outlet valve secured thereto, a passageway leading from the power cylinder port to said second piston, an opening from said passageway to said storage tank port comprising a priming port and a priming valve normally closing said priming port whereby a power stroke of said power piston will open the port leading to the chamber and will keep its outlet port closed and the retracting stroke will permit the outlet port and priming port to open.

2. A liquid pressure impulse regulator assembly, comprising a cylinder, a power piston within the cylinder, a casing opening to the cylinder, an inlet valve controlling the opening between the casing and the cylinder, resilient means holding the valve in closed position opposed to the piston, a reservoir supply passageway, a port from the casing leading to said passageway, an outlet valve controlling the flow from the casing adapted to be opened by pressure from within said casing, a second piston connected to said outlet valve outside of said casing, and a passageway leading from the cylinder to the rear of said second piston, whereby on a power stroke of the power

piston pressure is directed against the inlet valve to the casing which is thereby opened and the outlet valve is held in closed position and on the return stroke the inlet valve is closed and the outlet valve is opened.

3. A liquid pressure impulse regulator assembly, comprising a cylinder, a power piston within the cylinder, a casing opening to the cylinder, an inlet valve controlling the opening between the casing and the cylinder, resilient means holding the valve in closed position opposed to the piston, a reservoir supply passageway, a port from the casing leading to said passageway, an outlet valve controlling the flow from the casing, a second piston connected to said outlet valve, a conduit connecting the cylinder to the rear of the said second piston, a priming port from said conduit to the reservoir passageway and a valve controlling said priming port and operable by pressure from said passageway.

4. A liquid pressure impulse regulator assembly comprising a cylinder, a power piston within the cylinder, a casing to which pressure is to be supplied, a port between the cylinder and the casing, a valve controlling said port, resilient means urging said valve to closed position in a direction opposed to the power stroke of the power piston, a reservoir chamber, a port between the casing and said chamber, an outlet valve controlling said port, a second piston of larger area than said outlet valve secured to said valve, a passageway leading from said cylinder to behind said second piston, and a priming port connecting said passageway with said reservoir chamber.

5. A liquid pressure impulse regulator assembly comprising a cylinder, a power piston within the cylinder, a casing to which pressure is to be supplied, a port between the cylinder and the casing, a valve controlling said port, resilient means urging said valve to closed position in a direction opposed to the power stroke of the power piston, a reservoir chamber, a port between the casing and said chamber, an outlet valve controlling said port, a second piston of larger area than said outlet valve secured to said valve, a passageway leading from said cylinder to behind said second piston, a priming port connecting said passageway with said reservoir chamber, a valve controlling said port, and resilient means holding said valve in closed position but permitting it to be opened by pressure from the reservoir chamber.

6. A liquid pressure impulse regulator assembly comprising a casing from which liquid is to be pumped, a power cylinder, a power piston within the cylinder, a housing, a main chamber in said housing, a port connecting said chamber with the casing, a pressure port connecting said chamber with the cylinder, a valve controlling the pressure port, resilient means urging said valve into closed position opposed to said piston, another chamber in said housing, an outlet port connecting said outlet port, a second piston in said other chamber secured to said valve, a passageway leading from the cylinder to said other chamber behind said second piston, an outlet from said other chamber, a conduit leading from said outlet and a storage tank connected with said conduit.

7. A liquid pressure impulse regulator assembly comprising a casing from which liquid is to be pumped, a power cylinder, a power piston within the cylinder, a housing, a main chamber

in said housing, a port connecting said chamber with the casing, a pressure port connecting said chamber with the cylinder, a valve controlling the pressure port, resilient means urging said valve into closed position opposed to said piston, another chamber in said housing, an outlet port connecting said two chambers, a valve controlling said outlet port, a second piston in said other chamber secured to said valve, a passageway leading from the cylinder to said other chamber behind said second piston, a priming port between said passageway and said other chamber, a valve controlling said port, resilient means holding said valve in closed position toward said other chamber, an outlet from said other chamber, a storage tank and a conduit connecting said tank with said outlet.

8. An impulse regulator assembly comprising a casing to which pressure is to be supplied, a source of pulsating pressure, a supply pipe leading from said source to said casing, a valve controlling said supply pipe, resilient means urging said valve to close said supply pipe in a direction toward said source of pressure, a chamber, a port between the chamber and the casing, an outlet valve controlling said port, a piston secured to said outlet valve, a passageway leading from said power pipe to behind said piston, a priming port connecting said passageway with said chamber, a valve controlling said port and resilient means urging said valve to close said port in a direction opposed to pressure from said chamber.

9. A liquid pressure impulse regulator assembly comprising a cylinder, a power piston within the cylinder, a casing opening to the cylinder, an inlet valve controlling the opening

between the cylinder and casing, resilient means urging the valve in closed position from the casing side of the opening, a reservoir supply chamber, a passageway leading from said casing to said chamber, an outlet valve controlling said passageway, a piston connected to the chamber side of said outlet valve, a conduit leading from said cylinder to the rear of said valve piston and a conduit leading from said casing to said cylinder behind said power piston.

10. A liquid pressure impulse regulator assembly comprising a cylinder, a power piston within the cylinder, a casing opening to the cylinder, an inlet valve controlling the opening between the cylinder and casing, resilient means urging the valve in closed position from the casing side of the opening, a reservoir supply chamber, a passageway leading from said casing to said chamber, an outlet valve controlling said passageway, a piston connected to the chamber side of said outlet valve, a conduit leading from said cylinder to the rear of said valve piston, a conduit leading from said casing to said cylinder behind said power piston and a pressure accumulator connected in parallel with said conduit between the casing and cylinder.
